UNITED STATES PATENT OFFICE.

CHARLES H. LAWTON, OF TORRINGTON, CONNECTICUT.

SAFETY CHECK-BIT.

No. 892,748.

Specification of Letters Patent.

Patented July 7, 1908.

Application filed December 17, 1907. Serial No. 406,829.

To all whom it may concern:

Be it known that I, CHARLES H. LAWTON, a citizen of the United States, residing at Torrington, county of Litchfield, State of Connecticut, have invented a new and useful Safety Check-Bit, of which the following is a specification.

This invention has for its object to provide a safety check bit adapted for use in connection with an ordinary bit to provide a means for holding up a horse's head, to provide means for controlling a pulling horse and also to provide means for controlling a horse should the ordinary bit break in use. It is of course well understood that serious accidents occasionally occur through the breaking of an ordinary bit, which leaves the driver without any means for controlling the horse. I therefore term my novel bit a safety check bit as it performs all the functions of an ordinary check bit, so called, in holding up a horse's head and also provides a safety device which insures perfect control of a horse by the driver should the ordinary bit break. With these and other objects in view I have devised the novel bit which I will now describe, referring to the accompanying drawings forming a part of this specification and using reference characters to indicate the several parts:

Figure 1 is a front elevation illustrating my novel safety check bit as in use; Fig. 2 a similar view illustrating the operation of the safety check bit should the ordinary bit break; Fig. 3 a side elevation corresponding with Fig. 1; and Figs. 4, 5 and 6 are elevations from different points of view of my novel safety check bit detached.

10 denotes an ordinary bit which is provided with the usual side rings 11 to which the reins 12 are attached, and 13 the usual side straps of a bridle which are also attached to rings 11.

My novel safety check bit comprises a bar 14 provided at its ends with strap loops 15 and with eyes 16 for rings 17 to which supporting or over-draw check straps 18 are attached.

19 denotes a safety check strap, the mid-length of which forms a chin strap indicated by 20 and the ends of which are passed through loops 15 and then carried backward and attached to the reins as at 21. In practice, the ends of the safety check strap may 55 be attached to the reins by the usual rein

buckles 22, the free ends of the safety check strap being engaged in the usual retaining loops 23 which are made large enough to receive both the ends of the reins and of the safety check strap. The safety check strap 60 is shown as provided with a plurality of buckle holes 24 whereby it is made adjustable to meet the various requirements of use.

For an ordinary easy driving horse, the safety check strap may be left loose and the 65 safety check bit will have no function other than as a safety device that will come into use and provide means for controlling the horse should the ordinary bit break. For use upon a pulling horse, the safety check 70 strap would be drawn up more tightly so that the chin strap would grip more or less tightly and the safety check bit would be raised above the ordinary bit, as clearly indicated in Fig. 2, although said figure is intended to specially illustrate the operation of the safety check bit should the ordinary bit break in use. It will be noted in Fig. 1 that the safety check bit is made enough longer than the ordinary bit so that the safety 80 check bit will ride up over side rings 11. Should it be required to use the safety check bit to hold up a horse's head, the supporting or overdraw check straps are shortened more or less to raise the safety check bit so that it 85 will perform the functions of an ordinary check bit.

Having thus described my invention I claim:

1. The combination with a bit, of reins operatively connected thereto, a safety check bit, a strap having a mid-length portion to serve as a chin strap and connected with the safety check bit and to the reins, the connection with the reins being a positive 95 one to enable the said safety check bit to be used as a driving bit if the other bit should break.

2. The combination with a bit, of reins operatively connected thereto, a safety check 100 bit having supporting straps connected to it, and a safety check strap, the mid-length of which serves as a chin strap and the ends of which slide freely through the safety check bit and are operatively connected to the reins, 105 so that should the bit break a horse may be controlled by the safety check bit.

3. The combination with a bit, reins operatively connected thereto and supporting straps, of a safety check bit to which the 110

supporting straps are operatively connected and which is provided with strap loops, and a safety check strap the mid-length of which serves as a chin strap and the ends of which 5 pass freely through said strap loops and are adjustably and positively connected to the reins.

In testimony whereof I affix my signature, in presence of two witnesses.

CHARLES H. LAWTON.
